CLAIM

The ornamental design for an extrusion, as shown and described.

DESCRIPTION

FIG. 1 is a top perspective view of an extrusion showing our new design;

FIG. 2 is a left side elevational view thereof, the right side elevational view being a mirror image thereof;

FIG. 3 is a top plan view thereof;

FIG. 4 is a front elevational view thereof, the rear elevational view being a mirror image thereof; and,

FIG. 5 is a bottom plan view thereof.

The extrusion is shown with a symbolic break in its length. The appearance of any portion of the extrusion between the jagged break lines forms no part of the claimed design.
